US00D592658S

(12) **United States Design Patent**
Sugiyama et al.

(10) **Patent No.:** **US D592,658 S**
(45) **Date of Patent:** **** May 19, 2009**

(54) **DATA INPUT AND OUTPUT TERMINAL**

(75) Inventors: **Satoru Sugiyama**, Kawasaki (JP);
Manabu Hayahi, Kawasaki (JP);
Mariko Jinno, Tokyo (JP); **Takashi Matsuda**, Tokyo (JP)

(73) Assignee: **NEC Infrontia Corporation**,
Kawasaki-shi (JP)

(**) Term: **14 Years**

(21) Appl. No.: **29/301,393**

(22) Filed: **Feb. 27, 2008**

(30) **Foreign Application Priority Data**

Sep. 11, 2007 (JP) 2007-024767

(51) LOC (9) Cl. **14-02**

(52) U.S. Cl. **D14/336**

(57) **CLAIM**

The ornamental design for a data input and output terminal, as shown and described.

DESCRIPTION

FIG. 1 is a top, front, right side perspective view of a data input and output terminal showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a top, rear, left side perspective view thereof; and,

FIG. 9 is a right side view thereof showing a state in which a display part is moved.
